[57] CLAIM

The ornamental design for a high gain phacoemulsification needle, as shown and described.

DESCRIPTION

FIG. 1 is a perspective view of the present invention;

FIG. 2 is a front view of the present invention;

FIG. 3 is a top view of the present invention;

FIG. 4 is a side view of the present invention; and,

FIG. 5 is a bottom view of the present invention.

1 Claim, 1 Drawing Sheet

FIG. 3.

FIG. 1.

FIG. 2.

FIG. 4.

FIG. 5.
